Fokke Hamming, Huizen, Netherlands, assignor to Aarde-werkfabriek Haho N. V., Huizen (N. H.), Netherlands

Application August 11, 1954, Serial No. 31,820

Claims priority, application Netherlands March 30, 1954

Term of patent 14 years

(Cl. D85—2)

I claim:

The ornamental design for a combined humidor and ash tray cover, as shown.
